ATTACHMENT FOR MINING MACHINE
ANCHOR JACKS

James C. Buttrick, Scarbro, W. Va.

Application February 17, 1949, Serial No. 77,038

6 Claims. (Cl. 255—53)

1

My invention consists in new and useful improvements in an attachment for mining machine anchor jacks and relates more particularly to an improved anchor head adapted to be used in connection with jack pipes of the type generally employed in anchoring mining equipment during operation.

The primary object of my invention is to provide an anchor head which is designed to receive a conventional coal cutter bit for engagement with the mine roof, said head being so constructed that when being installed, the bit is positively forced into retaining engagement with the roof without the necessity of the machine operator cutting a hole in the roof to accommodate the jack pipe point, which has been one of the objectionable features of anchor jacks heretofore used. Frequently, mine roofs are composed of sandstone and in order to place an anchor jack in operation, it has been necessary to cut a hole in the sandstone which required extensive cutting with the attendant harmful production of silica dust which contributes to the occupational disease known as silicosis. As before stated, with my improved head this operation has been rendered unnecessary.

Another object of my invention is to provide in an anchor jack, a bit-receiving head which is angularly adjustable to compensate for varying angles of inclination of the jack body, so as, at all times, to maintain the cutting end of the bit in position for substantially vertical engagement with the mine roof.

A further object of my invention is to provide an angularly adjustable bit having a novel, transversely retractable fulcrum arrangement, whereby the bit can be quickly released from engagement with the mine roof by the simple turning of one screw.

With the above and other objects in view which will appear as the description proceeds, my invention consists in the novel features herein set forth, illustrated in the accompanying drawing and more particularly pointed out in the appended claims.

Referring to the drawing, in which numerals of like character designate similar parts throughout the several views:

Figure 1 is a view in side elevation partly broken away, showing my improved anchor jack in place in a mine;

Figure 2 is an enlarged sectional view through the anchor head showing the bit in released position in full lines, and in engaging position in dotted lines;

2

Figure 3 is a transverse sectional view taken on line 3—3 of Figure 2; and

Figure 4 is an enlarged detail of my improved bit fulcrum screw.

In the drawing, the numeral 5 represents a conventional jack pipe or anchor jack, adapted to be interposed between the roof 6 and floor 7 of an operation area in a mine, the lower end 8 of the jack pipe being sharpened for engagement with the floor 7. The upper end of the jack pipe 5 is adapted to receive the stem 9 of my improved anchor head 10 which supports the coal bit 11 for engagement with the mine roof 6, as will hereinafter appear.

The head 10 and its dependent stem 9 are integrally formed preferably of solid steel, the head being sufficiently enlarged to provide adequate strength for the performance of its functions.

As shown more clearly in Figs. 1 and 2, the head 10 is preferably shaped with an inclined face 12 through which a recess 13 is cut into the head, said recess terminating in an arcuate bottom or floor 14 and being substantially fan shaped in cross section. The bit 11 rests loosely in the recess 13 with its inner end normally engaging the arcuate floor 14 and its outer end projecting through the opening 15 in face 12, which forms the mouth of the recess 13.

The bit 11 may be a conventional coal bit, the cutting end 16 of which is preferably tipped with stellite and turned upwardly at an angle, as will be seen from Fig. 2, said tip being sharpened for engagement with the roof 6 of the mine.

The under side of the bit is fulcrumed on a screw or pin 17 which extends transversely through the head 10 with the central portion of its shank lying across the recess 13, adjacent the mouth 15. One side of the periphery of

this central portion of the shank of screw 17 is recessed as at 18 to receive the under side of the bit 11, and the shank is screw threaded to engage complementary threads in the head 10. Thus, the screw may be turned in the head to

bring the recess 18 into and out of registry with the under side of the bit 11 for the purpose hereinafter set forth.

The top face of the head 10 is provided with a boss 19 which is drilled and threaded to receive a threaded adjusting screw 20 which is preferably disposed at substantially right angles to the bit 11 in the recess 13 and is of sufficient length for its inner end 20a, to operatively engage the lower portion of the bit at a point below the fulcrum pin 17. Thus, by adjusting the position of the

screw 20 the angular disposition of the bit 11 may be varied on its fulcrum.

If desired, I may provide an auxiliary set screw 21 which extends through one of the side walls of the head 10 and projects into recess 13 for engagement with the side of the bit 11. The purpose of this auxiliary set screw is to retain the bit in place when the device is not in use and, as will later appear, to facilitate the longitudinal or outward adjustment of the bit under certain conditions.

In operation, the jack pipe 5 with my improved anchor head 10 in place, is installed for its usual purpose, between the floor and ceiling of an operation area in a mine with the point 8 engaging the floor and the cutting end 16 of the bit 11 engaging the roof 6. In order to insure the proper vertical direction of the cutting end 16 in its engagement with the roof 6, the relative angular position of the bit 11, with respect to the body 5 of the jack pipe, is adjusted by rocking the bit on its fulcrum 17 through adjustment of the screw 20. When the bit is being set, the fulcrum pin 17 is turned to a position with the non-recessed, cylindrical portion of its shank in engagement with the under side of the bit 11 and this position of the pin 17 is maintained during the entire period of engagement of the bit with the roof of the mine.

By turning the screw 20 inwardly, its inner end 20a abuts the lower portion of the bit, rocking the latter on its fulcrum 17, the leverage thus created, positively forcing the cutting end 16 into the roof 6 of the mine, to an effective depth diagrammatically illustrated by the line x-x in Figure 2. This avoids the necessity of the operator cutting a hole in the roof of the mine to receive the bit. Obviously, if the height of the roof 6 with respect to the floor 7, is such as to require a more acute angle in positioning the jack pipe 5, this may be compensated for by adjusting the screw 20 in the head 10 to cause the cutting end 16 of the bit 11 to assume a substantially vertical line of engagement with the roof 6, the engagement being maintained so long as the screw 20 abuts the upper side of the bit 11.

When it is desired to release the anchor jack, the simple turning of the fulcrum pin 17, to bring its recessed portion 18 under the bit 11, retracts the axis of the fulcrum and permits the bit to drop, bringing its cutting end 16 to the released position shown in full lines in Fig. 2, at a level illustrated diagrammatically by the line y-y.

The auxiliary set screw 21 is generally employed for the purpose of preventing displacement of the bit 11 from the head 10 when the device is not in use. By simply tightening the screw 21, its inner end engages the side of the bit 11 and retains it in place. Under certain conditions, it may be necessary to extend the bit 11 longitudinally outwardly and in this event the set screw 21 cooperates with the adjusting screw 20 to retain the bit in its projected position. However, under normal conditions and for assuring the greatest degree of support, the lower end of the bit 11 rides in engagement with the arcuate floor 14 of the recess 13.

It will thus be seen that I have provided a practical and efficient anchor head which is simple in construction, easy to install and positive in its action. Furthermore, by the use of this device many of the hazards heretofore encountered in connection with conventional mining jacks are eliminated. For example, it is known

that methane gas often collects in crevices in the roof of a coal mine and the digging of a hole in the sandstone roof of a mine with a pick as is necessary with the conventional type of jack, is likely to cause sparks which will result in an explosion from the accumulated methane gas. Obviously this hazard is avoided by the use of my device which as before stated, eliminates the necessity of digging a hole in the mine roof.

From the foregoing it is believed that my invention may be readily understood by those skilled in the art without further description, it being borne in mind that numerous changes may be made in the details of construction without departing from the spirit of the invention as set forth in the following claims.

I claim:

1. In a mining machine anchor jack, including an elongated body having means at one end for engaging one of two vertically spaced mine surfaces; an anchor head carried at the opposite end of said body and having a bit-receiving cavity, opening to the exterior adjacent the upper portion of said head, a bit loosely mounted in said cavity with its cutting end protruding through said opening, a transverse fulcrum for said bit, and an adjustable abutment extending into said cavity for engagement with said bit at a point below its fulcrum, to regulate the angle of presentation of said bit to the adjacent mine surface.

2. In a mining machine anchor jack, including an elongated body having means at one end for engaging one of two vertically spaced mine surfaces; an anchor head carried at the opposite end of said body and having a bit-receiving cavity, opening to the exterior adjacent the upper portion of said head, a bit loosely mounted in said cavity with its cutting end protruding through said opening, a transverse fulcrum for said bit, and an adjustable abutment extending into said cavity for engagement with said bit at a point below its fulcrum, to regulate the angle of presentation of said bit to the adjacent mine surface, said fulcrum being transversely retractable to release the engagement of said bit with said mine surface.

3. In a mining machine anchor jack as claimed in claim 2, wherein said fulcrum comprises a transverse pin having a peripheral recess in one side adapted to receive the adjacent portion of said bit, said pin being rotatable in said head to alternately bring said recess and the normal periphery of said pin, into engagement with said bit, whereby the effective axis of said fulcrum may be varied.

4. In a mining machine anchor jack, including an elongated body having means at one end for engaging one of two vertically spaced mine surfaces; an anchor head carried at the opposite end of said body, said head having a bit-receiving cavity, opening to the exterior adjacent the upper portion of the head, a bit disposed in said cavity with its cutting end protruding through said opening, a transverse fulcrum member in said cavity for said bit, and adjustable means extending into said cavity, operatively engaging said bit at a point below its fulcrum for rocking said bit to regulate the penetrating engagement of its cutting end with the adjacent mine surface, said fulcrum being adjustable for varying its effective axis.

5. In a mining machine anchor jack, including

an elongated body having means at one end for engaging one of two vertically spaced mine surfaces; an anchor head carried at the opposite end of said body, a bit-receiving cavity in said head having an opening to the exterior adjacent the upper portion of the head, said cavity having substantially parallel side walls connected by end walls which diverge from said opening, a bit having one end loosely mounted in said cavity for movement between said diverging end walls and having an upturned cutting end protruding through said opening, a transverse fulcrum in said cavity for said bit, adjacent said opening, and an adjustable abutment extending into said cavity for engagement with said bit at a point below its fulcrum, to regulate the angle of presentation of the cutting end of said bit to the adjacent mine surface, said fulcrum being transversely retractable to release said engagement with the mine surface.

6. A mining machine anchor jack as claimed

in claim 5, wherein said bit is longitudinally shiftable in said cavity and including a set screw in at least one side wall of said cavity adapted for engagement with said bit for locking the same in a selected longitudinal position in said cavity.
